Patented Jan. 28, 1975

234,183

STUCCO PAINT SCRAPER

Joseph A. Malnar, 628 San Gabriel,
Albany, Calif. 94706

Filed June 14, 1973, Ser. No. 370,023

Term of patent 14 years

Int. Cl. D7—05

U.S. Cl. D7—184

FIG.—1

FIG.—2

FIG.—3

FIG. 1 is a top plan view of a stucco paint scraper showing my new design;

FIG. 2 is a bottom plan view thereof; and

FIG. 3 is a side elevation view thereof.

I claim:

The ornamental design for a stucco paint scraper, as shown.
